WILLIAM ARTHUR COOK, OF MARION, INDIANA, ASSIGNOR TO MARION MACHINE,
FOUNDRY & SUPPLY COMPANY, OF MARION, INDIANA, A CORPORATION

LUBRICATING MEANS FOR MACHINES

Application filed October 26, 1925. Serial No. 64,906.

This invention is an improvement in means for the automatic lubrication of machines of various kinds and particularly band wheel power mechanism commonly employed in driving the pumps of a number of oil wells. The invention has been made with particular reference to the latter purpose, although it is not limited to any particular form of machine where the gravity feed of the oil to the parts of the machine is employed. The use of a pump for automatically returning the oil to the top of the machine whereby it can be fed down by gravity through the machine and to the parts thereof and collected in a reservoir from which it is again returned to the pump, is broadly old, but my present invention has certain important improvements over lubricating systems of this type as will hereafter appear.

One feature of the invention consists in having an annular reservoir in the stationary lower part or base of the machine concentric with the vertical shaft of the machine in which reservoir there is provided means for the operation of a pump, which extends down into the reservoir and is revolved therein. The particular means in the reservoir herein provided is an annular cam track in the reservoir upon which a roller on the lower end of the pump plunger travels and whereby the pump is operated.

Other features of the invention relate to the means at the upper end of the machine for receiving the oil from the pump and distributing it to the parts of the machine through which it afterwards moves by gravity back to the reservoir, as will more fully hereafter appear.

The full nature of the invention will be understood from the accompanying drawings and the following description and claims:

In the drawings, Figure 1 is a view of the machine showing the major portion thereof in central vertical section and other portions

in elevation, parts being omitted. Fig. 2 is a plan view of the upper hub flange with the cap thereon removed and the shaft in cross section and the spokes broken partially away. Fig. 3 is a plan view of the eccentrics and base of the machine. Fig. 4 is a section of a portion of the upper eccentric on the line 4-4 of Fig. 3. Fig. 5 is a plan view of the base showing the shaft in section. Fig. 6 is a central vertical section of the pump. Fig. 7 is a section through the base and lower eccentric on the line 7-7 of Fig. 3, parts being broken away. Fig. 8 is a vertical section of the upper eccentric on the line 8-8 of Fig. 3, but on a smaller scale.

The machine herein shown for illustrating this invention is what is called a band wheel power. It has a stationary base 10 having a vertical cup bearing 11 in the middle thereof for the lower end of the stationary shaft 12. The upper end of said shaft is held by brace rods, not shown. There is a hub 15 on said shaft for the band wheel 16 that is horizontally disposed and is held in place by an upper series of spokes 17, connected to the ears 18 on the upper hub flange 19 and a lower series of spokes 20 connected to the ears 21 on the lower hub flange 22. The band wheel 16 is driven by a belt, not shown, extended from an engine or other forms of power also not shown.

The power is transmitted to pumps at oil wells by rods, not shown, connected with eccentric rings 25 which surround eccentrics 26 that are fixedly connected with the hub so as to rotate therewith on the shaft 12. Thus, the eccentrics and hub and hub flanges and band wheel constitute a rigid unit and supported by a suitable bearing 27 on the base 10. Any desired number of eccentrics may be used but usually there are two as here shown, and they extend in opposite directions.

The general features of the mechanism shown and so far described, are old and in

general use but this invention relates to the means for automatically lubricating said machinery. Since these machines are out in the field in the country and scattered and 5 may operate continuously for long periods of time, the lubrication thereof is of great importance for their continuous and proper operation.

In a machine herein shown the base has 10 an oil reservoir 30 which is concentric with the shaft and it is supplied through the connections 31 and 32 with oil from a distant oil tank 33, located wherever it is most convenient. In the bottom of this reservoir 30 there 15 is a cam track 35 that is continuous and concentric with the shaft and its upper surface rises and falls substantially as shown.

The pump 36 is mounted vertically in the lower eccentric 26 so as to extend down into 20 the reservoir and in vertical alignment with the cam track. The pump plunger 136 carries on its lower end a roller 37 which rides and travels upon the cam track 35 as the pump is carried around in its revolutions by 25 the lower eccentric 26, and thereby the plunger is elevated and a spring 137 in the tubular stem 38 of the plunger returns the plunger and holds it down on the track. The upper end of the spring 137 is held in place by a 30 screw plug 39. The oil is taken up through a passageway 40 in the pump. This passageway extends through a removable nipple 41, at the upper end of which there is a check 35 valve 42, and said passageway communicates with the cylinder of the pump through the chamber 44. On the down stroke of the 40 plunger the oil is drawn up into the cylinder of the pump and on the up stroke of the plunger it is forced out through chamber 44, past check valve 45 into pipe 46 which 45 communicates with a pipe 47 that extends vertically through the upper eccentric and the two hub flanges 22 and 19, and at its upper end said tube is turned downward at 48 so as to discharge the oil through an opening 49 of a cover or cap 50 into an oil receiver 51 surrounding the shaft.

The oil which has been elevated by the 50 pump mechanism described and discharged into the oil receiver 51 is distributed to the machine for lubricating it by the following means. The oil receiver 51 is in an oil chamber 52 which is divided into two compartments by the annular rib 53. The inner compartment 54 immediately surrounds the shaft and oil is supplied to it through the ports 55 in the oil receiver 51, and the oil from chamber 54 passes down by gravity between the shaft and hub thereon and between the shaft 55 and the eccentrics and to the bearing that supports the structure on the base.

The oil passes from the oil receiving chamber through ports 60 to the outer oil chamber 52 at the top and thence through tubes 61 and 65 62 that extend through the upper and lower

hub cap, outside the hub, and the lower ends of said tubes project into oil pockets 63 and 64 in the upper eccentric 26. From each of said oil pockets there is an outwardly extending conduit 65 leading to the bearing surface between the eccentric and the eccentric ring 25 for lubricating the same. The oil from said bearing surfaces descends to and is received by an annular reservoir 66 in the outer periphery of the eccentric and extending beyond the same like a lip under the eccentric ring as shown. From this reservoir 66 there is a drain tube 67 which extends down into the oil pockets 63 and 64 in the lower eccentric 26, and from the annular reservoir 66 in the lower eccentric the oil returns through drain pipe 67 to the main reservoir 30 in the base as seen in Fig. 7. From the oil pockets 63 there are overflow passages 68 and 69 leading down through the upper eccentric 85 and discharging into a pocket 63 or 64 in the lower eccentric and counter overflow passages in the lower eccentric discharging into the main reservoir 30 in the base.

The invention claimed is:

1. In apparatus of the kind described, a stationary base having a central portion and an open-top oil reservoir surrounding said central portion, a vertical shaft with its lower end mounted in said central portion of the base, a machine part mounted on said shaft and horizontally revolvable above said base, a vertical pump carried by said revolvable machine part which extends down into said reservoir in the base and is revolved thereby 90 concentric with said shaft so as to travel annularly in said reservoir, a vertically-acting plunger in said pump, a roller on the lower end of the plunger, an upwardly-extending cam track in the bottom of the reservoir and surrounding said central portion of the base and concentric with said shaft in position for said roller to travel thereon as the pump revolves and whereby the pump plunger is operated, a conduit leading from the pump for discharging oil from said reservoir to the upper end of the machine, whereby the oil can be fed by gravity through the machine for lubricating the same, and means for returning said downwardly-moving oil to said reservoir.

2. In apparatus of the kind described, a stationary base with a central upwardly-extending portion and an open-top annular oil reservoir entirely surrounding said central portion, a vertical shaft with its lower end mounted in said central portion of the base and centrally of said reservoir and extending above the base, machine parts mounted on said shaft which revolve horizontally above said base, an annular vertically-extending cam track on the bottom of said reservoir and concentric with said shaft, a pump carried by a revolving part of the machine so that the pump will project downwardly into and 125

travel in said annular reservoir with its piston vertically arranged to travel above said cam track, a roller on the lower end of the piston which rides upon said cam track for operating the pump, an oil reservoir in the upper part of the machine surrounding said shaft, a conduit leading from the pump discharging the pumped oil to said reservoir, and drain conduits leading from said upper reservoir through the machine parts and extending and discharging into said oil reservoir in the base.

In witness whereof, I have hereunto affixed my signature.

15 WILLIAM ARTHUR COOK.
